UNITED STATES PATENT OFFICE.

GEORGE B. HAYNER, OF CANON CITY, COLORADO.

INCUBATOR.

No. 913,957.

Specification of Letters Patent. Patented March 2, 1909.

Application filed September 4, 1907. Serial No. 391,344.

To all whom it may concern:

Be it known that I, GEORGE B. HAYNER, a citizen of the United States, residing at Canon City, in the county of Fremont and 5 State of Colorado, have invented certain new and useful Improvements in Incubators, of which the following is a specification, reference being had therein to the accompanying drawing.

10 My invention relates to improvements in incubators and heaters therefor and it consists in the novel construction and the combination and arrangement of parts hereinafter described and claimed.

15 One object of the invention is to provide an improved hot water heater which may be readily removed from the incubator or brooder to which it is applied, for repairing, cleaning or other purposes.

20 Another object of the invention is to provide an improved means for controlling the flame of the lamp burner of the heater.

25 A further object of the invention is to improve and simplify the construction and operation of devices of this character and thereby render the same more convenient, reliable and efficient.

The above and other objects, which will 30 appear as the nature of the invention is better understood, are accomplished in the preferred embodiment of the invention illustrated in the accompanying drawings, in which—

Figure 1 is a vertical longitudinal section 35 through the incubator and its heater; Fig. 2 is a perspective view of the heater and one end of the incubator; Fig. 3 is a perspective view of the flame controlling sleeve; and Fig. 4 is a similar view of the lever for operating the same.

In the drawings, 1 denotes the body of the incubator which may be of any well known or preferred form and construction and which has a removable top or cover 2 adapted 45 to be secured by screws or other fastenings. In one end of the body at its top is formed a vertical slot 3 for the reception of the flow and return pipes 4, 5 of the hot water heater which latter consists of a tank 50 or boiler 6 and a plurality of connected pipes 7.

Suitably secured to the pipes 4, 5 of the heater is a supporting plate 8 which is adapted to be fastened by screws or the like upon the slotted end of the body 1 so as to close 55 the upper portion of the slot 3. The plate 8 serves as a means for securing the heater in the incubator and supporting one of its ends. The other end of the heater within the body may be supported by a bracket 9 or in any 50 other suitable manner.

From the foregoing it will be seen that by removing the fastenings for the cover 2 and the plate 8, said parts may be removed from the body and that when the plate 8 is removed the heater will be removed with it.

Any arrangement of the heating pipes within the incubator may be employed but the one illustrated in Fig. 1 consists in extending the flow pipe 4 to the far end of the 70 body 1 and connecting it to the center of a cross pipe 10 from the ends of which project pipes 11. The latter are connected at their opposite ends by a cross or end pipe 12 to the center of which is connected the return pipe 75 5. The pipes 4, 5 communicate with the tank 6 in different horizontal planes so as to create a circulation of water through the system of pipes.

The heater tank 6 has its bottom formed 80 with a dome 13 to provide a heat retaining chamber 14 into which projects the upper end of a stationary chimney 15. The latter is supported concentrically in the chamber 14 by a perforated or apertured annular flange 85 16 which unites it to the lower part of the bottom of the tank, as clearly shown in Fig. 1. Upon this lower portion of the bottom of the tank is arranged a drain cock 17 and upon the top of the tank is a filling opening 90 or connection 18 provided with a screw cap or other suitable closure.

The numeral 19 denotes the body of an oil lamp which has an ordinary burner comprising a wick tube 20 and a surrounding flange 95 or support 21 for a movable chimney 22. The lamp is supported beneath the tank 6 upon a bracket having a vertical portion 23 secured by screws or the like to the body 1 and a horizontal portion 24 having a seat or 100 recess to receive the body 19 and in which the latter is secured by a set screw 25. The

chimney 22 is adapted to slide within the stationary chimney or pipe 15 depending from the tank and it is preferably constructed of metal and has a sight opening covered by transparent material. Around the lower end of the chimney section 22 extends a reinforcing wire 26 which has a portion twisted to form a laterally projecting finger piece 27 by means of which the said chimney section 10 may be readily raised and lowered into and out of the section 15 to expose or cover the upper portion of the burner. When the chimney section 22 is lowered it is supported by the flange or portion 21 of the body and 15 when elevated it is supported by engaging the finger piece 27 with a keeper 28 in the form of an angular plate secured to and depending from the chimney section 15. The section 22 is adapted to turn, as well as slide 20 in the section 15 so that by rotating it slightly the finger piece 6 may be engaged with or disengaged from the shoulder or projection upon the keeper, as will be readily understood.

25 For the purpose of controlling the size of the flame of the lamp burner, I provide a controller sleeve 29 which is adapted to fit around and slide upon the wick tube 20. This controller 29 is formed from a single 30 piece of metal which is suitably cut and bent as shown at Fig. 3 so that its vertical edges are separated to provide in one of its sides a vertical opening 30 which is provided for the purpose of preventing the flame of the lamp 35 from being entirely extinguished when the controller is raised to the limit of its upward movement, as hereinafter described. Projecting outwardly from the opposite sides of the lower end of the controller or sleeve 29 40 are apertured ears 31 adapted to loosely receive the arms of a fork 32 provided upon one end of a lever 33 which has at its other end an enlargement formed in one face with a seat or recess 34. This lever is adapted to 45 extend through and swing in a slot formed in the chimney flange 21 of the burner and is fulcrumed by loosely resting in the forked upper end of a bracket 35 projecting from one side of the lamp body. The seat 34 in 50 the lever is adapted to receive the lower end of an adjustable operating rod 36 which is actuated by a lever 37 suitably fulcrumed and projecting through a slot in the body of the incubator. This lever has its inner end 55 arranged so that it will be actuated by a thermostat 38 which may be of any suitable form and construction, and the outer end of said lever is apertured to receive the upper threaded end of the rod 36. An adjusting 60 nut 39 is provided upon the threaded portion of said rod for engagement with the lever 37, as clearly shown in the drawings. By means of the nut 39 it will be seen that the

flame controlling sleeve 29 may be normally positioned at any desired point upon the wick tube so that as the temperature in the body 1 fluctuates, the lever 37 will be actuated by the thermostat and its movement will be imparted by the rod 36 to the lever 33 of the controller. 70

By reason of the construction just described it will be seen that the parts may be readily adjusted and readily separated for cleaning or repairing. By raising the chimney section 22 and securing it in its elevated 75 position, as above described, and then depressing the outer end of the lever 33, the rod 36 may be removed and the sleeve 29 may then be disengaged from the lever 33 and taken off of the wick tube. When this is done 80 the lever 33 may be lifted out of its bracket 35 and removed from the burner by drawing its end 34 through the slot in the flange 21.

From the foregoing it will be seen that as the controlling sleeve is shifted vertically 85 upon the upper end of the wick tube it will regulate the size of the flame so that the water in the heater may be maintained at a constant temperature and that by reason of the slot or opening 30 in said sleeve the flame 90 will not be extinguished even when the sleeve is raised to the limit of its upward movement. The heat arising from the flame of the burner is discharged from the chimney section 15 against the center of the dome 13 and is deflected to the sides of the same, and then 95 passes downwardly and out through the perforations in the flange 16.

Having thus described my invention what I claim and desire to secure by Letters Patent is:—

The combination with an incubator body having an opening in one of its walls, and a lamp for heating the incubator, of a thermostatically controlled lever projecting 105 through the opening in the incubator and having its outer end apertured, a flame controlling sleeve slidably mounted on the wick tube of the burner and formed in one side with a vertical opening extending from top 110 to bottom and adapted to admit air to the wick in the wick tube to prevent the lamp from being extinguished when the controlling sleeve is raised to reduce the flame, outwardly projecting apertured ears at opposite points 115 upon the controlling sleeve, a fulcrum bracket upon the lamp and provided with a U-shaped upper end, a removable lever loosely fulcrumed in said U-shaped end of the bracket and having one of its ends bifurcated to provide spaced arms which project through and slide in the apertured ears on said controlling sleeve, the other end of the last mentioned lever being formed with an enlargement having a depression arranged vertically beneath 120 the opening in the first mentioned lever, a

readily removable connecting rod having its lower end removably seated in the depression in the second mentioned lever and its upper end screw threaded and projecting through 5 and slideable in the aperture in the outer end of the first mentioned lever, and a milled adjusting nut upon the threaded upper end of the connecting rod and bearing against the

bottom of the outer end of the first mentioned lever, substantially as shown and described. 10

In testimony whereof I hereunto affix my signature in presence of two witnesses.

GEORGE B. HAYNER.
